Attorney, Agent, or Firm—Testa, Hurwitz & Thibeault, LLP[57] **CLAIM**

The ornamental design for a sample vial, as shown and described.

DESCRIPTION

FIG. 1 is a front perspective view of a sample vial, showing our new design;

FIG. 2 is a side elevational view of the vial;

FIG. 3 is a top plan view of the vial; and,

FIG. 4 is a bottom plan view of the vial.

The broken line showing of the knurling on the cap portion is for illustrative purposes only and forms no part of the claimed design.
